UNITED STATES PATENT OFFICE.

LEO J. GRUBMAN, OF NEW YORK, N. Y., ASSIGNOR TO VOICES, INCORPORATED, OF NEWARK, NEW JERSEY, A CORPORATION OF DELAWARE.

SOUND-PRODUCING DEVICE.

Application filed August 7, 1923. Serial No. 656,169.

This invention relates to sound producing devices and more particularly to a device of that type which is incorporated with in the body of a doll for the purpose of 5 simulating an infant cry such as the exclamation "ma-ma".

It is the primary object and purpose of my present improvements to provide a device of the above character wherein the several 10 co-operating parts are very compactly housed and arranged within a shell or casing of relatively small dimensions, thus enabling the device to be readily mounted within the body of a comparatively small 15 size doll.

Sound producing devices of this type are primarily characterized by the co-operative association of an air expelling member, a sound producing means and a sound emission 20 controlling means and it is one of the prominent features of my present disclosure to arrange and combine such parts in the form of a single unit mounted and supported within the casing or housing for operative movement relative to the walls thereof. 25

It is another object of the invention to provide a sound producing device of the bellows type having the usual flexible body 30 wall securely fixed at one of its ends to the casing or housing and having an air expelling head at the other end thereof carrying the sound producing and sound emission controlling means and movable within the casing to and from positions on opposite 35 sides of the fixed end of the bellows wall. In this manner, I aim to provide for the requisite air expelling movement of the bellows head, and yet confine or house the parts within a casing of comparatively short 40 length.

It is also one of the detail objects of my present improvements to provide an improved construction and mounting of the sound producing reed. 45

With the above and other objects in view, the invention consists in the improved sound producing device and in the form, construction and arrangement of its several 50 parts as will be hereinafter more fully described, illustrated in the accompanying

drawings and subsequently incorporated in the subjoined claims.

In the drawings wherein I have disclosed one simple and practical embodiment of the invention and in which similar reference characters designate corresponding parts throughout the several views;

Figure 1 is an end elevation of the device;

Figure 2 is a longitudinal section thereof; 60

Figure 3 is a side elevation with one of the casing parts shown in section;

Figure 4 is a horizontal section taken on the line 4—4 of Figure 3, one of the parts being broken away; 65

Figure 5 is a horizontal section taken on the line 5—5 of Figure 2;

Figure 6 is a fragmentary plan view of one element of the air expelling head, the sound producing reed being removed therefrom; and 70

Figures 7 and 8 are detail elevations of said element.

In sound producing devices of the type with which my present improvements are 75 more particularly identified, it has heretofore been the practice in the art to secure the flexible bellows wall at one of its ends to one end of the housing or casing while to the other end of said wall a gravity movable air expelling head is suitably secured, said head being guided in its movement by a central tubular post and the head and post provided with coacting means to control the emission of the sound. Owing to the 80 fact that the air chamber must have a certain capacity and the air expelling head a certain extent of movement in one direction to expel the air and produce the desired sounds, it was necessary to provide a casing 85 or housing of comparatively large size, particularly as to its lengthwise dimension for the purpose of housing the parts. In such prior art construction, the sound producing reed is mounted within the tubular post. 90

In other constructions, the reed is mounted in a chamber provided on the bellows head and the central guide rod or post for said head is provided with spaced discs which control the emission of sound from the 100 chamber. I propose to entirely eliminate the use of such a central rod or post and to

also materially reduce the lengthwise dimension of the casing or housing in such a bellows type of sound producing device and at the same time produce a very realistic simulation of the infant cry, "ma-ma".

To this end, I have illustrated a practical embodiment of my present improvements in the accompanying drawing wherein I have shown the casing or housing constructed in two parts 5 and 6, respectively. These casing parts may be stamped from heavy cardboard, sheet metal, or other suitable material, each of said parts preferably being of cylindrical form and open at one of its ends. At its open end, the circumferential wall of the casing part 6 is laterally offset or formed with the flange 7 to thus produce an internal annular shoulder 8 thereon.

The other casing part 5 has spaced internal annular beads 9 formed in its circumferential wall, the purpose of which will hereinafter appear, while the end wall of said casing part is provided with a multiplicity of sound emission apertures 10.

The flexible membrane or bellows wall 11 is securely fixed and frictionally clamped at one of its end edges between the inner face of the flange 7 on the casing part 6 and the end of the circumferential wall of the casing part 5 which is telescopically fitted within said flange, the end edge of said wall also acting to tightly clamp the bellows wall upon the annular shoulder 8.

To the other end of the flexible bellows wall 11 the air expelling head is attached. In the present instance, I have shown this air expelling head as consisting of the two members 12 and 13, respectively. Each of these members is in the form of a relatively heavy sheet metal stamping, the member 12 having a marginal wall 14 provided with a laterally disposed outwardly projecting annular flange 15. The other member 13 is also formed with a marginal wall 16 and within this wall the member 12 is adapted to be nested. The other end edge of the flexible membrane or bellows wall 11 is first engaged around the end of the wall 16 so that when the member 12 is inserted, said end edge of the bellows wall will be tightly clamped and frictionally held between the marginal walls 14 and 16 of said members and between the end edge of the wall 16 and the flange 15. It will be noted that the marginal wall 16 of the member 13 is of greater depth than the wall 14 of the member 12 and the central portion of the end wall of the member 13 is outwardly offset as indicated at 17. There is thus provided between these two members a sound modifying chamber 18. Outwardly of the offset portion 17 the member 13 is provided with a plurality of spaced sound emission orifices 19 communicating with the chamber 18.

The member 12 of the air expelling head

carries the sound producing reed. The mounting and arrangement of this reed constitutes one of the important features of my present disclosure and is therefore illustrated in detail in Figures 2, 5 and 6 of the drawings. Upon reference thereto it will be seen that the wall of the member 12 is offset in its intermediate portion to provide a diametrically extending recess 20 therein, one end of which is widened or enlarged as 75 at 21, the wall of the member 12 at this widened end of the recess being pressed outwardly to form a pocket 22, said pocket wall being separated at one of its ends from the wall of the depression 20 and thereby providing communication between said pocket and the sound modifying chamber 18.

In the depression 20 the sounding reed 24 is positioned, said reed being in the form of a thin flat vibratory element of sheet 85 metal, hard rubber, fibre, celluloid or other suitable material and having one end thereof extending within the enlarged end 21 of said recess or depression and in overlying relation to the pocket 22. It will be noted from reference to Figure 2 of the drawing that this end portion of the sounding reed is slightly spaced from the opposite side edges of the pocket 22 so that the air as it is expelled in the movement of the air expelling head from one end of the casing or housing is forced around the sounding reed through said pocket, thereby causing the reed to vibrate and produce the sound waves which issue from the pocket 22 into the chamber 18. 100

The sounding reed is firmly held in the depression 20 by means of a suitable leaf spring 25 pivotally secured at one end by the rivet 26 to the member 12. Preferably, a pad of cardboard or other suitable material, shown at 27, is interposed between the leaf spring and the reed element 24. In the insertion of the reed element and the pad 27 the leaf spring is turned upon the pivot 26 to one side of the depression 20 and then subsequently returned to a position in parallel relation with the depression and in resilient bearing contact upon the pad 27.

It will be noted that the maximum dimension of the air expelling head is appreciably less than the internal dimension of the casing or housing, thus affording ample space for the flexible membrane or bellows wall 11 to fold upon itself in the movements of said head. The final issuance of the sound from the apertures 10 in the end wall of the casing is controlled by a disc 28 of hard rubber, fibre, cardboard or other suitable material, said disc being securely fixed upon the portion 17 of the member 13. As disclosed, I preferably position a plate 29 upon the central part of said disc and permanently secure said plate and the disc to the member 13 by means of the rivet 30. It will be observed that the disc is of somewhat 130

greater diameter than the air expelling head and its free or unsecured marginal portion overlies and projects beyond the air emission orifices 19 in the wall of the member 13.

Having above described the several structural features of the device, its operation may be explained as follows:

Assuming that the internal parts are momentarily disposed in the position indicated in Figure 3 of the drawings, upon the downward movement of the air expelling head within the casing, the air contained between the flexible wall or membrane 11 of the bellows and the walls of the casing part 6 is forcibly expelled therefrom and as it passes around the reed element through the pocket 22, the sound waves are produced and disseminated in the chamber 18 from which they issue through the orifices 19. At the start of this operative movement of the air expelling head, it will be seen that the edge of the disc 28 will first engage the uppermost internal rib or bead 9 on the wall of the casing part 6, thus muffling or subduing the issuance of the sound waves around said disc so that they pass through the apertures 10 in the end wall of the casing and are finally audible as a close simulation of the spoken pronunciation of the letter M. Upon the continuance of the gravity movement of the air expelling head and during the passage of the edge of the disc 28 between the spaced beads or ribs 9, a greater space is afforded for passage of the sound waves around the disc and into the end of the casing so that the sound next issues from the apertures 10 as a simulation of the spoken pronunciation of the letter a. When the edge of the disc 28 encounters the second or lowermost groove or bead 9, the letter m is again sounded and when said disc passes below said latter bead, there will be a comparatively prolonged sounding of the letter a until the air expelling head reaches a position of rest at the end of its gravity movement.

It will be apparent that it is optional in the use of such a device to so form the ribs 9 on the casing wall that when the edge of the flexible disc engages therewith, there may be a slight leakage of sound in restricted volume around the edge of the disc, or, on the other hand, such issuance of sound completely cut off, and the restricted emission of sound provided for by the provision of a bleed hole or a small orifice through the bellows head, such latter alternative being common practice in the art.

It will be apparent from a comparison of Figures 2 and 3 of the drawings that in this operation of the device the air expelling head moves within the casing or housing from a position at one side of the fixed end of the bellows membrane or wall 11 to a position substantially at the opposite side

of said fixed end of the bellows wall. By securing the fixed end of the bellows wall at a point intermediate of the limits of movement of the air expelling head within the casing, I am thus enabled to obtain the forcible expulsion of a sufficient volume of air to fully sound the several syllables of the word and at the same time materially reduce the lengthwise dimension of the casing in comparison with that required for other devices of an analogous character as heretofore known in the art. It will be seen that in my new construction the air expelling member, the sound producing means and the sound emission controlling element are combined in the form of a single unit which is wholly suspended relative to the walls of the casing solely by means of the flexible wall or membrane of the bellows. In other words, this composite or unitary structure may be said to have a full floating mounting within the casing or housing since no part thereof has a fixed connection with the walls of the casing. Accordingly, frictional resistance to the proper free and unretarded operation of the several elements is wholly eliminated and the proper functioning of the device for the intended purpose is positively assured. In view of the very compact arrangement of the several parts and the small dimensions of the housing or casing, it is possible to readily mount the device in operative position within the body of a comparatively small size doll, whereas in so far as I am aware, prior art devices of this type could only be utilized in connection with dolls of appreciably greater size.

In the present disclosure, I have referred to an embodiment of the invention which is believed to be highly satisfactory in practical operation. However, it is possible that corresponding results might be obtained in other alternative constructions, and it is accordingly to be understood that no limitations are to be implied from the foregoing detail description, and that I reserve the privilege of adopting all such legitimate changes as may be fairly embodied within the spirit and scope of the invention as claimed.

I claim:

1. In a sound producing device, an air chamber and a movable head constituting one end of said chamber, a sound producing reed through which the air flows in the movement of said head in one direction, a wall surrounding said head, said head having means thereon cooperating with said wall to provide a sound emission passage between said means and the wall, and means affording communication between said reed and said passage.

2. In a sound producing device, a casing having apertures in the wall thereof, sound

- 1 producing and sound emission controlling means combined in a single unit, and a flexible wall fixed at one of its ends to the casing and at its other end to said unit, said 5 wall subdividing the interior of the casing diametrically thereof into air receiving and sound receiving chambers and suspending said unit for free floating operative movement relative to the casing walls.
- 10 3. In a sound producing device, an air chamber, a movable head constituting one end of said chamber, a sound producing reed through which the air is expelled from said chamber in the movement of said head in one direction, a wall surrounding said head, said head having means thereon cooperating with said wall to provide a sound emission 15 passage, means affording communication between said reed and said passage, and said 20 wall having means thereon with which the means on said head coacts to obstruct the emission of sound through said passage.
4. In a sound producing device, a casing having sound emission apertures in the wall thereof, a cylindrical bellows having a flexible tubular body wall fixed at one end to the casing, an air expelling head secured to the other end of said flexible wall and movable within the casing to and from positions on 25 opposite sides of the first named fixed end of the bellows wall, sound producing means through which the air is expelled, and means controlling the emission of sounds from said casing.
- 30 5. In a sound producing device, a casing having sound emission apertures in the wall thereof, said casing wall being also provided with spaced annular internal ribs, sound producing means, a bellows arranged within the casing having a gravity movable head for expelling air through the sound producing means, and a sound emission controlling element carried by said head and coacting with said spaced ribs to restrict the 35 passage of sound in the movement of the head in one direction, said element cooperating with the casing wall to provide sound emission passages.
6. In a sound producing device, a casing having sound emission apertures in the wall thereof, said casing wall being also provided with spaced annular internal ribs, sound producing means, a bellows arranged within the casing having a gravity movable head 40 for expelling air through the sound producing means, and a flexible sound emission controlling disc carried by said head and coacting with said spaced ribs in the movement of the head in one direction.
- 55 7. In a sound producing device, an air chamber and a movable head constituting one end of said chamber, a sound producing reed through which the air is expelled from said chamber in the movement of said head in one direction, a wall surrounding said 50 head, means on one of said parts cooperating with the other part to provide a sound emission passage between said part and said means during the air expelling movement of said head, and means affording communication 55 between said reed and said passage.
8. In a sound producing device, an air chamber and a movable head constituting one end of said chamber, a sound producing reed through which air is expelled from said 60 chamber in the movement of said head in one direction, a wall surrounding said head, a sound controlling and directing element on one of said parts cooperating with the other part to provide a sound emission passage 65 therebetween during each of successive increments of movement of the air expelling head, and means affording communication between said reed and said passage.
9. In a sound producing device, an air chamber, a movable head constituting one end of said chamber, a sound producing reed through which the air is expelled from said chamber in the movement of said head in one direction, a wall surrounding said head, a sound controlling and directing element on one of said parts cooperating with the other part to provide a sound emission passage 70 therebetween, means affording communication between said reed and said passage, and said latter part having spaced means thereon with which said element coacts to obstruct the emission of sound through said passage a plurality of times during the air expelling movement of said head.
10. In a sound producing device, a casing, a bellows within said casing having a flexible body wall fixed at one of its ends to the casing wall, an air expelling head fixed to the other end of said flexible wall, a sound producing reed through which the air is expelled from said bellows in the movement of said air expelling head, and a sound directing and controlling element carried by said head and cooperating with the wall of said 75 casing to provide a sound emission passage between said element and the casing wall, means affording communication between said reed and said passage, and said casing wall having spaced parts with which said element coacts to obstruct the emission of sound through said passage a plurality of times during the air expelling movement of said head.
11. In a sound producing device, a casing, a bellows within said casing having a tubular flexible body wall fixed at one of its ends, an air expelling head fixed to the other end of said flexible wall, sound producing means operated by air expelled from the bellows in the movement of said head, a sound controlling and directing element carried by said head and cooperating with the casing wall to provide an annular sound emission passage 80 between said element and the casing.

wall, means affording communication between said sound producing means and said passage, and said casing wall having means thereon obstructing the emission of sound through said passage during the air expelling movement of the bellows head.

12. In a sound producing device, a wall having an opening therein and a depression in one side of said wall leading to said opening, a vibratory sound producing element seated in said depression with an end por-

tion thereof projecting over said opening, a cushioning pad engaged upon the part of said element in the depression, and a spring mounted on said wall and yieldably engaging the cushioning pad to retain the sound producing element in operative relation to said opening. ¹⁵

In testimony that I claim the foregoing as my invention, I have signed my name hereunder. ²⁰

LEO J. GRUBMAN.
